SEWING KIT

Heinrich Kruft, Dusseldorf, Germany

Application February 4, 1955, Serial No. 34,367

Claims priority, application Germany December 17, 1954

Term of patent 7 years

(Cl. D3—19)

Fig. 1

Fig. 2

Fig. 3

Fig. 1 is a top plan view of a sewing kit according to my new design;

Fig. 2 is an edge view thereof looking in the direction of the arrows 2—2 of Fig. 1; and

Fig. 3 is a horizontal sectional view thereof taken on the line 3—3 of Fig. 1.

The sewing implements shown in broken lines in Fig. 1 of the drawing are for illustrative purposes only.

I claim:

The ornamental design for a sewing kit, substantially as shown and described.
